TAB REMINDER DEVICE

La. Bron R. Allen, Juanita H. Allen, and Ruth L. Kabitsch, Cincinnati, Ohio; assignors to Signet, Ltd., Cincinnati, Ohio

Application September 16, 1947, Serial No. 774,392

7 Claims. (Cl. 116—134)

1

This invention pertains to indicating devices and is particularly directed to devices for reminding a person of an item or series of items to be purchased. More particularly, this invention pertains to a tab reminder device which is small, compact, and portable and which may be preset for the desired items to be purchased as these items come to mind and which may be readily carried in the purse or pocket to the store for making the specific purchases set up in the reminder device.

One of the objects of this invention is to provide a reminder device in the form of a compact item having a series of indicating tabs showing various types and kinds of items to purchase.

Another object of this invention is to provide a neat portable tab indicating device having a series of subject tabs pivotally mounted in a leather covering case which may be conveniently folded up in compact form and carried in the purse of the purchaser.

Still another object of this invention is to provide a compact portable item indicating device which may be preset from time to time prior to the making of actual purchases for the particular items ultimately wanted; the whole device being self-contained in a leather enclosure adapted to be carried on the finger or in the pocket or purse of the purchaser.

And a still further object is to provide in a tab reminder device an arrangement for preselecting desired tabs of items to be purchased which locks and holds the selected tabs while at the same time serving as a carrying ring for holding the reminder device on the purchaser's finger.

It is also an object of this invention to provide a tab reminder device which not only indicates the specific items to be purchased but also indicates the manufacturer, trade name, and the like of the respective items so as to effect spot sales advertising at the time of purchase of such items as indicated by the tab reminder device.

Figure 1 is a plan view showing the tab reminder device in opened condition for preselection of tabs.

Figure 2 is an end view of the tab reminder device of Figure 1.

Figure 3 is a side view of the device shown in Figure 1.

Figure 4 is a view similar to Figure 1 but showing the various pivotally mounted tabs dispersed and the selected tabs locked in position by the carrying ring.

Figure 5 is an end view of the device in Figure 4

showing the user's finger inserted in the locking and carrying ring of the reminder device.

Figure 6 is a fragmentary side view of the device shown in Figure 5.

Figure 7 shows the tab reminder device folded up for carrying on the finger or placement in the purse or pocket of the purchaser.

Figure 8 is an end view of the closed device in Figure 7.

As an exemplary form of this invention, there is shown a tab reminder device having the main cover piece 10, which is preferably made of leather, plastic, or other pliable material, in the center of which is located a pivot post 11 upon which are carried the various item reminder tabs 12. These tabs are each embossed, printed, or otherwise marked with the names of the various items to be purchased and associated with these main names it is also preferable to indicate the trade-mark, the manufacturing concern, or the distributor of the particular type of item to be selected so as to provide spot sales advertising at the same time giving the indication of the item that should be purchased.

Also mounted on the main cover 10 is a locking and carrying ring strap 13 which may be passed through slots 14 and 15 so as to form a continuous loop of suitable material so that the ring may be pulled toward the inside of the cover 10, as shown

in Figures 1, 2, and 3, in such a way that the selected tabs 12a may be slipped under the ring 13 from time to time as the prospective purchaser's thoughts indicate certain items are to be purchased in the future. In other words, the housewife, for example, may normally have the reminder device laying conveniently on the kitchen table with the tabs fanned out as at 12b in the position shown in Figure 4 and, as different items come to mind during the day, the various tabs 12a

may be slipped under the ring 13. When it comes time to go to the store to make the purchases, the tabs are all folded together and the locking and carrying ring 13 pulled transversely to the outside of the cover locking the selected tabs 12a securely in position as shown in Figure 4. The finger F is then passed through the ring as shown

in Figures 5 and 6 to hold the ring 13 to securely lock the selected tabs 12a while at the same time providing a carrying means for the tab reminder device.

The case member 10 is then folded over and held together by suitable snap button 16 and cooperating snap fastener 17 as shown in Figure 5. When in the closed form of Figures 7 and 8, it is obvious that the entire reminder de-

vice is small and compact and convenient to carry on the purchaser's finger or in the purse or pocket and may be readily opened or unwrapped for examination of the selected tabs to remind the purchaser quickly and accurately of the items to be bought. It should also be noted that those items which it has been impossible to purchase at the time may be still indicated by retaining those tabs under the ring 13 while swinging the purchased tabs back to the position 12 in Figure 1. Thus, at a subsequent time, items still remaining under the ring 13 will not be overlooked.

While the apparatus herein disclosed and described constitutes a preferred form of the invention, it is to be understood that the apparatus is capable of mechanical alteration without departing from the spirit of the invention and that such mechanical arrangements and commercial adaptations as fall within the scope of the appended claims are intended to be included herein.

Having thus fully set forth and described this invention, what is claimed as new and desired to be secured by United States Letters Patent is:

1. In a tab reminder device, a flexible closure member, a series of indicator tabs, means for pivotally mounting said tabs by one end at a central point in said closure cover, a combined locking and carrying ring mounted on said closure cover to one side of said pivotal mounting adapted to receive and secure a series of selected tab indicators to said cover, and fastening means on said closure member adapted to hold said closure in wrapped position around said indicator tabs, pivot, and strap.

2. In a tab reminder device having a flexible closure cover, a series of indicator tabs pivotally mounted at a central point on said cover, and a combined confining strap and carrying ring on one portion of said cover to one side of said pivotal mounting for receiving and securing a selected series of said tabs, the remaining portion of said tabs being disposed together on the opposite side of said pivot from said strap so that said closure may be wrapped around all of said tabs.

3. In a tab reminder device having a flexible closure cover, a series of indicator tabs pivotally mounted at a central point on said cover, and a transversely movable confining ring and carrying device on one portion of said cover to one side of said pivotal mounting for receiving and securing a selected series of said tabs, the remaining portion of said tabs being disposed together on the opposite side of said pivot from said strap so that said closure may be wrapped around all of said tabs, and fastening means for holding said closure cover in wrapped position around said tabs.

4. In a portable tab reminder device, a flexible cover member, a pivot post in the center of said

cover member, a series of tab reminders pivotally connected at one of their ends to said post whereby said tabs may be swung around said pivot for examination of data marked on the face of said tabs, and a restricting and carrying strap mounted on said cover to one side of said pivot adapted to receive a series of selected tabs and retain them for specific reference separate from all of the other tabs remaining on the opposite side of said pivot post from said strap.

5. In a portable tab reminder device, a flexible cover member, a pivot post in the center of said cover member, a series of tab reminders pivotally connected at one of their ends to said post whereby said tabs may be swung around said pivot for examination of data marked on the face of said tabs, a combined retaining and carrying ring mounted on said cover to one side of said pivot adapted to receive a series of selected tabs and retain them for specific reference separate from all of the other tabs located on diametrically opposite side of said pivot post from said strap, and means whereby said cover may be wrapped around said thus positioned indicator tabs including a fastener device for holding said cover in wrapped position.

6. In a portable tab reminder device, a cover piece formed with a pair of spaced openings, a flexible loop slidably mounted on said piece in said openings and presenting loop portions on opposite sides of said cover piece, and a plurality of tab reminders pivotally carried by said cover piece, any of said tab reminders being adapted to be selectively confined by the loop portion on the corresponding side of said cover piece.

7. In a portable tab reminder device, a cover piece formed with a pair of spaced openings, a flexible loop slidably mounted on said piece in said openings and presenting loop portions on opposite sides of said cover piece, a pivot post carried by said cover piece on one side thereof, and a plurality of tab reminders pivotally mounted on said post, each of said tab reminders being adapted to be selectively positioned within and confined by the loop portion on the corresponding side of said cover piece.
